PRINTING-TELEGRAPH SYSTEM.

1,086,695.

Specification of Letters Patent. Patented Feb. 10, 1914.

Application filed December 20, 1912, Serial No. 737,851. Renewed October 22, 1913. Serial No. 796,733.

To all whom it may concern:

Be it known that we, ARTHUR H. ADAMS and AMOS F. DIXON, citizens of the United States, residing at Brussels, in the Kingdom of Belgium, and at Newark, in the county of Essex and State of New Jersey, respectively, have invented a certain new and useful Improvement in Printing-Telegraph Systems, of which the following is a full, 10 clear, concise, and exact description.

This invention relates to printing telegraphs, and more particularly to a printing telegraph receiver in which the characters are selected and the other necessary operations controlled by a combination of two impulses received over either one or both of two main line conductors, and in which the second impulse of a combination is never of the same character as that of the first.

20 The object of this invention is to provide a printing telegraph apparatus of the above type, which is reliable, rapid and efficient in operation and which will perform all the necessary functions with a small number of 25 elements.

To the above end type controlling magnets provided with two windings are arranged in groups, each winding of a magnet being in a different group. Means are also provided 30 whereby the first impulse received selects and holds energized a group of windings containing one winding of the desired magnet; and a second impulse selects and holds energized a second group of windings containing the other winding of the desired 35 magnet. Novel means are likewise provided for the controlling of the printing operation and the various other functions to be performed.

40 This invention will be fully understood from the following description taken in connection with the accompanying drawings, in which—

Figures 1 and 2 combined illustrate diagrammatically a complete receiving system, 45 and in which so much of the mechanical details as are necessary to understand the operation thereof are shown in perspective.

The invention is shown operating in connection with the selecting apparatus covered 50 by the copending application of Oscar A. Danielson, Serial No. 760,232, filed April 10, 1913, although it may be used in connection with other selecting circuits, as for ex-

ample, that covered by patent to C. E. 55 Scribner and A. H. Adams, No. 1,056,064, dated March 18, 1913.

In Fig. 1 the main line conductors L¹ and L² are shown connected to polarized relays 1, 2 and 3, 4, respectively. The relays are 60 polarized by means of a current furnished by a battery 5. Connected with the armature contact of the polarized relays 2 and 3 are a plurality of branches of magnets and 65 relays which are adapted to be selected in a predetermined arrangement upon the receipt of a combination of impulses over the main line conductors. The windings of these magnets and relays are arranged in two 70 groups or branches, the upper branch containing, for example, the upper windings of the type magnets 31, 21, 61 and 51, and the reset relay 41, together with the winding of a string relay 10; the lower branch containing the lower windings of type magnets 75 16, 15, 14, 13 and 12. The other upper branches are provided with string relays 20 to 60, and each string relay is adapted upon energization to close a locking circuit through a branch of lower windings. 80

The type magnets are arranged in a circle about the type shaft 6, which carries a type wheel 7 as shown at the right of Fig. 2. Each magnet is provided with an armature 8 which is adapted when attracted to project an end thereof into the path of a lever 9 carried by the shaft 6. The type wheel 7 is thereby arrested in a position to present a predetermined character to the printing platen. An impulse arriving over one or 90 both of the main line conductors passes through and energizes one or a group of the polarized relays of a selecting means, which, in turn, closes a circuit through an upper branch of type magnet windings and a string 95 relay. The string relay is thereupon energized, completing a locking circuit for itself and the upper branch or group through a lower branch or group and the starting relay 105. The type shaft thereupon starts to rotate in the direction of the arrow in Fig. 2. A second impulse of the combination arriving at either one or both of the main line conductors passes through and energizes a 110 different one or group of the polarized relays 105 and thereupon closes a circuit through another branch or group of type magnet windings. One type magnet now has both of its 115

windings energized and attracts its armatures to arrest the type wheel 7.

A sufficient description of the circuit and apparatus will appear from the operation 5 of selecting a predetermined type magnet, the shift, space, reset and paper lift magnets. Let it be assumed that the operator at the distant end of the main line conductors desires to print the character D, and further 10 assume that the character D is selected and printed by a combination of two impulses consisting of positive current over line conductor L^2 followed after an interval of no current by a second impulse of negative current 15 over line conductor L^1 . When the positive impulse over line conductor L^2 is sent from the distant station it passes through the positively polarized relay 3 to ground and back to battery at the transmitting station. A positive impulse over line conductor 20 L^2 passes through the upper winding of the relay 3, and the magnetic flux through the core of said relay caused by this impulse is in the same direction as the flux in the core 25 caused by the constant current from the battery 5, with the result that the armature of said relay is attracted, closing a circuit which may be traced from battery 101, through the upper winding of the type magnets 53, 63, 30 13, 23 and 43, in series in the order named, the string relay 30, armature of the relay 3, armature of the relay 1, guard relay 102, to ground and back to battery. When the string relay 30 is energized it attracts its 35 armature completing a circuit from battery 101, through the type magnets 53, 63, 13, 23, 43 and string relay 30 as above named, lower windings of type magnets 31, 32, 34, 35 and 36 in series in the order named, conductor 40 103, conductor 104, starting relay 105, armature of the clearing-out relay 106, to ground and back to battery. The guard relay 102 also draws up its armature but performs no function at this stage of the selection beyond 45 shunting the starting relay 105 and preventing its operation until the cessation of the impulse. The first impulse is now at an end and the polarized relay 3 returns to normal. The starting relay 105 is energized 50 attracting its armature, closing a circuit which may be traced from battery 107, starting magnet 108, armature of the starting relay 105, to ground and back to battery. The starting magnet 108 attracts its armature 55 109, which moves the pawl 110 from engagement with the ratchet 111, allowing the type shaft 6 to revolve under the influence of spring 112. The circuit traced from the battery 101 through the windings of the 60 various type magnets and the starting relay 105 remains locked up at the armature of the string relay 30. The second impulse of the assumed combination of impulses was negative battery impressed on line conductor 65 L^1 , and as a result of this impulse the nega-

tively polarized relay 2 is energized attracting its armature. The energization of the relay 2, when it attracts its armature, closes a circuit from battery 115, reset relay 41, upper windings of type magnets 52, 62, 12, 32 and the paragraph relay 42 in series in the order named, string relay 20, armature of the relay 2, through the guard relay 102, to ground and back to battery. The completion of this circuit causes the energization 70 of the guard relay 102, and the string relay 20. The former by attracting its armature, prevents the printing operation from being performed until after the completion of the second impulse. The attraction of the armature of string relay 20 closes a circuit for the lower windings of type magnets 21, 23, 24, 25 and 26 from ground at the armature 75 of the clearing-out relay 106. It will be noted, however, that the string of windings last named forms a bridge between the circuit, which includes the upper and lower windings of the type magnets, closed at the armature of string relay 30 and the circuit 80 including the upper windings of the type magnets in series with the winding of string relay 20. The amount of current flowing through this bridge is, therefore, so small that the armature of any type magnet therein will not be attracted even though current 85 is flowing through the other winding thereof. Also it will be observed that a stronger current than that in the bridge circuit is now flowing through each of the windings of the type magnet 32, which thereupon attracts its armature, and the outer end of armature 8 thereof is moved upwardly into the path of the arm 9 attached to the now 90 rotating type shaft 6, and when the arm 9 contacts with the outer end of said armature 95 the type shaft 6 is stopped in such position that the selected character on the type wheel 7 is in proper position to print the character selected. At the cessation of the second impulse of the combination, the 100 armature of the guard relay 102 is retracted, closing a circuit which may be traced from battery 116, armature of the guard relay 102, conductor 117, clearing-out relay 106, upper winding of the space-lock relay 118, conductor 119, printing magnet 120, arm 9 on the type shaft 6, the end of the selected type magnet armature 8, to ground and back to battery. The closure of this circuit accomplishes the following: The printing magnet 110 115 is energized causing the printing of the selected character on the paper or record medium. The armature of the space-lock relay 118 is attracted closing a locking circuit for the same from battery 121, through the spacing magnet 122, conductor 123, armature of the space-lock relay 118, lower winding thereof, armature of the reset relay 41, to ground and back to battery. The clearing-out relay 106 is energized at 125 130

tracting its armature breaking the selecting circuit for the selected type magnet. The energization and locking up of the space-lock relay 118 is to insure that the spacing magnet 122 will perform its function irrespective of what happens to the selecting circuit. The closure of the circuit through the spacing magnet 122 will therefore cause it to attract its armature 124, and the pawl 125 on the arm 126, contacting with the ratchet 127, rotates the drum 128 thus moving the paper carriage forward through the space of one character to insure a clean surface on which to print the next succeeding character.

The energization of the clearing-out relay 106 closes a circuit through the retractor relay 135 which may be traced from battery 136, retractor relay 135, armature of the clearing-out relay 106, to ground and back to battery. The retractor relay 135 attracts its armature and closes a circuit which may be traced from battery 137, retractor magnet 138, conductor 139, armature of the retractor relay 135, to ground and back to battery, in this manner energizing the retractor magnet 138 which attracts its armature moving the pawl 110 at the end thereof into engagement with the ratchet 111 on the type shaft 6, and rotating the same in a direction contrary to its normal direction of rotation a sufficient distance to break the contact heretofore described as existing between the arm 9 and the end of the armature of the selected type magnet. As the selected type magnet has been deenergized by the breaking of the selecting circuit at the armature of the clearing-out relay 106, this armature will be returned at once to normal position.

The removal of the arm 9 from engagement with the end of the armature 8 breaks the circuit from battery 116, through the clearing-out relay 106, the space-lock relay 118, and printing magnet 120. The clearing-out relay 106 and printing magnet 120 allow their armatures to return to normal position, but the armature of the space-lock relay 118 will still be attracted as it will be remembered that a locking circuit for said relay exists from battery 121, through its lower winding and armature. When the armature 124 of the spacing magnet 122 is fully attracted, the arm 140 thereon brings springs 141 into engagement with each other, which closes a shunt around the space-lock relay 118, which thereupon releases its armature breaking the energizing circuit for the spacing magnet 122. Immediately the armature 124 is retracted, contact is broken between the springs 141 destroying the shunt which was placed around the relay 118, and all parts of the device return to normal position. The other characters may be selected and printed in a manner analogous to that described above for the letter D.

If it is desired to print any of the characters shown on the lower row of type, it is necessary that a combination of impulses be sent from the transmitting station to select and operate the type shift magnet 145. The combination of impulses to accomplish this result is a negative impulse over line L^2 followed by a positive impulse over lines L^1 and L^2 simultaneously, the two impulses being separated by the usual interval of no current. The first impulse of this combination energizes the negatively polarized relay 4, which attracts its armature and completes a circuit from battery 146, upper winding of the shift-lock relay 147, conductor 148, through the upper windings of type magnets 54, 64, 14, 24, 34 in series in the order named, string relay 40, armature of the relay 4, guard relay 102, to ground and back to battery. The string relay 40 is energized attracting its armatures, the attraction of the lower armature of the string relay 40 completing a locking circuit for the type magnets and string relay, which may be traced from the battery 146, through the shift-lock relay 147, type magnets, string relay 40, through conductor 149, the lower windings of paragraph relay 42, reset relay 41, spacing relay 43, shift relay 45, backshift relay 46, conductor 104, conductor 150, upper armature of the string relay 40, conductor 151, armature of the starting relay 105, armature of the clearing-out relay 106, to ground and back to battery. It will be noted that this circuit provides a shunt about the winding of the starting relay 105, preventing its operation. The circuits just traced remain locked up after the cessation of the first impulse.

The second impulse was assumed to be positive battery over lines L^1 and L^2 simultaneously, and this impulse will energize the positively polarized relays 1 and 3 which attract their armatures, closing a circuit which may be traced from battery 101, through the upper windings of type magnets 65, 15, 25 and 35, in series in the order named, shift relay 45, string relay 50, upper armature of the polarized relay 3, lower armature of the polarized relay 1, guard relay 102 to ground and back to battery. The string relay 50 attracts its armature but as in the selection of a type magnet the lower windings of type magnets 51, 52, 53, 54 and 56 form a bridge across the selecting branches and receive a small amount of current. It will be noted that current is now passing through both windings of the shift relay 45, which thereupon attracts its armatures with the following result: A circuit is closed through the shift-lock relay 147 which may be traced from battery 146, lower winding of the shift-lock relay 147, conductor 152, armature of shift relay 45, to ground and back to battery, in this man-

ner preparing a path for current from battery 146 to the shift magnet 145. At the cessation of the second impulse of the combination of impulses the clearing-out relay 106 is energized, by current through a circuit from battery 116, armature of guard relay 102, conductor 117, clearing-out relay 106, conductor 153, resistance 154, conductor 155 to ground at the armature of the shift relay 45, sending the selecting circuit back to normal, and the shunt around the shift magnet 145 is broken at the armature of the shift relay 45, energizing the type shift magnet 145 through the following circuit: battery 146, the lower winding of the shift lock relay 147, conductor 156, type shift magnet 145, conductor 157, armature of the backshift relay 46, conductor 158, armature of the reset relay 41, to ground and back to battery. The type shift magnet 145 attracts its armature 160 moving type wheel 7 longitudinally of the type shaft 6 and bringing the lower row of characters thereon into printing position. The energizing circuit of the type shift magnet 145 remains closed or locked up at the armatures of the reset relay 41 and backshift relay 46 until one or the other of said relays is energized.

If it is desired to send the type wheel 7 back to its normal position without resetting the paper carriage, a combination of impulses is sent from the distant station to select and energize the backshift relay 46 which attracts its armature breaking the locking circuit for the type shift magnet 145, which retracts its armature 160, forcing the type wheel 7 longitudinally of the type shaft 6 and bringing the lower row of characters on said type wheel into printing position. The clearing-out relay is energized after the cessation of the second impulse by current flowing from battery 116, armature of guard relay 102, conductor 117, clearing-out relay 106, conductor 153, resistance 154, upper armature of shift lock relay 147, armature of back-shift relay 46, armature of reset relay 41 to ground and back to battery. The energization of the clearing-out relay sends the apparatus back to normal as hereinbefore described.

To provide a space between successive words a combination of impulses is sent from the distant station to select and energize the spacing relay 43, closing a circuit from battery 116, armature of guard relay 102, conductor 117, clearing-out relay 106, energizing winding of space lock relay 118, armature of spacing relay 43, armature of reset relay 41, to ground and back to battery. The closure of this circuit energizes clearing out relay 106 sending the selecting circuit back to normal. Also it energizes the space lock relay 118 which attracts its armature closing a circuit which may be traced from battery 121, spacing magnet 122, conductor 123, armature and holding winding of the space lock relay 118, armature of the reset relay 41, to ground and back to battery. The closure of this circuit causes a momentary energization of the spacing magnet 122, which attracts its armature 124, moving the pawl 125 on the arm 126 into engagement with the ratchet 127, moving the same in the direction of the arrow shown in Fig. 2, winding the cord 161 on the drum 128, and moving the carriage 162 across the machine through a distance equal to the space of one character. The turning of the drum 128 increases the tension in the spring 163, as the carriage is moved forward step by step, either in response to an energization of the spacing magnet alone, or the spacing magnet in connection with any printing cycle, sufficiently to insure a return of the carriage to normal upon the energization of the reset magnet 164. The space-lock relay 118 acts in this selection, as in the ordinary type selection, to insure that the spacing magnet 122 will perform its function.

The paper carriage 162 may be reset from any part of its stroke, and to accomplish this the reset relay 41 is selected and energized. The energization of the reset relay 41 causes it to attract its armature and closes a circuit which may be traced from battery 165, reset magnet 164, conductor 166, armature of the reset relay 41, to ground and back to battery. The closure of this circuit energizes the reset magnet 164 which attracts its armature 167, and the pin 168, coming into engagement with the side of the slot 169 on the pivot arm 170, moves the end thereof out from engagement with the ratchet 127, and the spring 163 rotates the drum 128 returning the carriage 162 to its normal position.

When the end of a line has been reached and it is desired not only to return the paper carriage to its normal position but to move the paper or record medium across the face of the paper carriage to provide a clean surface on which to print the succeeding line of characters, it is necessary to send from the distant station such a combination of impulses as will select and operate the paragraph relay 42. It will be noted that a combination of impulses to accomplish this result will not only select and operate the paragraph relay 42, but will also select and operate the reset relay 41. The combination of impulses to accomplish this result is a negative impulse over line L² followed by a second negative impulse over line L¹. The first impulse of this combination by energizing relay 4, closes a circuit through the upper windings 54, 64, 14, 24, 34, string relay 40, lower windings 42, 41, 43, 45, 46 and at its cessation, a shunt is placed around the

starting relay 105 to prevent the release of the type shaft, as has been hereinbefore described. The second impulse of the combination energizes the relay 2, closing a circuit which may be traced from battery 115, upper windings 41, 52, 62, 12, 32, 42, in series in the order named, string relay 20, top armatures of the relays 2 and 4, guard relay 102, to ground and back to battery. Current is now passing through both windings of the relays 42 and 41, and their armatures are attracted. The attraction of the armature of reset relay 41 closes a circuit which may be traced from battery 165, reset magnet 164, conductor 166, armature of reset relay 41, to ground and back to battery. The reset magnet 164 attracts its armature 167, and the pin 168 thereon coming into engagement with side of the slot 169, moves the pawl 170 out of engagement with the ratchet 127, allowing the drum 128 to rotate under the influence of its spring, and the carriage 162 is moved to its normal or initial position by the cord 161.

When the carriage 162 returns to its normal position, the pin 171, on the drum 128, moves into engagement with the pin 172, forcing the arm 173 rearward and moving the contact spring 174 into engagement with the contact spring 175, and completing a circuit which may be traced from battery 180, the magnets 181 of the paper-lift mechanism 182, conductor 183, armature of the paragraph relay 42, conductor 184, contact springs 174 and 175, conductor 185, conductor 166, armature of the reset relay 41, to ground and back to battery. The closure of this circuit energizes the magnets 181, and the slideable arm 187 of the paper-lift mechanism moves forward into engagement with the pivoted arm 188, gripping the paper therebetween and lifting the paper upward across the face of the paper carriage 162 a sufficient distance to insure a clean surface on the paper or record medium for the succeeding line of characters. When the armature 189 of the paper-lift mechanism 182 is attracted the insulating button 190 on the end of one arm of the angular member 191 forces the contact spring 192 into engagement with the contact spring 193, closing a circuit which may be traced from battery 116, conductor 117, clearing-out relay 106, conductor 153, resistance 154, conductor 153, conductor 194, contact springs 192 and 193 to ground and back to battery, energizing thereby the clearing-out relay 106, which attracts its armature breaking the selecting circuit for the paragraph and reset relays 42 and 41, respectively, and allowing all parts of the selecting circuit to return to normal position.

As there are but thirty distinct combinations of impulses used in this selecting system, and as there are thirty-one distinct op-

erations to be performed, it is necessary, in order to accomplish this result, to have one combination of impulses perform two distinct functions. As all the letters used are on the upper row of characters on the type wheel 7, and as it is never necessary to back shift unless the type wheel has been shifted and locked in shifted position, the combination of impulses that will select and energize the back shift relay 46 has also been used to select and energize the Z type magnet. The operation of selecting and energizing the Z type magnet is therefore slightly different from the selection and operation of any of the other type magnets, and this selection and operation will now be described. It will be assumed, of course, that the type wheel is in its normal position, that is, with the upper row of characters thereon in printing position.

The combination of impulses to select and operate the Z type magnet (and the back shift relay 46) is a negative impulse over line L² followed by a negative impulse arriving simultaneously over lines L¹ and L³. A negative impulse over line L² passes through the upper winding of the relay 4, and the armature of said relay is attracted closing a circuit which may be traced from battery 146, the upper or holding winding of the shift-lock relay 147, conductor 148, type magnets 54, 64, 14, 24 and 34 in series in the order named, string relay 40, armatures of the relays 2 and 4, guard relay 102, to ground and back to battery. As the circuit from this battery only passes through the holding winding of the shift-lock relay 147, this relay is not operated but the string relay 40, which is in the circuit traced, attracts both its armatures, closing at its lower armature a circuit which may be traced from said armature, through the conductor 149, paragraph relay 42, reset relay 41, spacing relay 43, shift relay 45, back shift relay 46, conductor 104, starting relay 105, armature of the clearing-out relay 106, to ground and back to battery. The upper armature of said string relay 40 closes a break point in a shunt circuit around the starting relay 105, preventing said relay from operating. This shunt circuit may be traced from the resistance 201, through conductor 150, upper armature of string relay 40, conductor 151, to the armature of the starting relay 105. The second impulse of the combination of impulses energizes both of the negatively polarized relays 2 and 4 which attract their armatures and complete a circuit which may be traced from battery 146, through the upper winding of the shift-lock relay 147, conductor 148, conductor 202, through the windings of the type magnets 56, 16, 26, 36 and 46, in series in the order named, through the string relay 60, lower armature of the relay 2, and upper armature of the relay 4,

through the guard relay 102 to ground and back to battery. The relay 46, it will be noted, has current passing through both its windings, and a circuit is closed which may be traced from battery 107, starting magnet 108, the Z type magnet 203, upper armature of the shift-lock relay 147, armature of the relay 46, armature of the reset relay 41, to ground and back to battery. It will be noted at this point that the selection just described is slightly different from the ordinary type selection in that the starting magnet for starting the rotation of the type shaft 6 is operated simultaneously with the attraction of the armature of the Z type magnet 203; that is, the type shaft 6 is not released until after the beginning of the second impulse of the selecting combination, whereas in the ordinary type selection it is released at the end of the first impulse. When the arm 9 carried by the now rotating shaft 6 strikes the end of the armature 8 of the Z type magnet 203 the type wheel is stopped in a position to print this character, and at the cessation of the second impulse, a circuit is completed through the clearing-out relay 106, space-lock relay 118 and printing magnet 120 as hereinbefore described. The operation of the clearing-out relay 106 restores the selecting circuit to normal condition and causes the operation of the retractor magnet 138 as in the ordinary type selection.

What we claim is:

1. In a printing telegraph system, a plurality of branch circuits; a plurality of type magnets therein, each having two windings, the two windings for each of said magnets in different branches; means in one of said plurality of branches for closing a circuit through a second of said branches; and means for consecutively closing said first branch and a third of said plurality of branches to energize both windings of a predetermined type magnet.
2. In a printing telegraph system, a plurality of branch circuits; a plurality of type magnets therein, each having two windings, the two windings for each of said magnets in different branches; means for closing one of said plurality of branches; means in said branch for closing and holding closed a second branch to energize one winding of a predetermined type magnet; and means for closing a third of said plurality of branches to energize the other winding of a predetermined type magnet.
3. In a printing telegraph system, the combination of a selecting circuit comprising a plurality of branches; a plurality of type magnets therein, each having two windings, the two windings for each of said magnets in different branches; a rotatable type shaft carrying a plurality of characters thereon; means controlled by both of said windings for stopping said shaft to bring any of said

characters into printing position; means in one of said plurality of branches for closing a second of said plurality of branches; selecting means for consecutively closing one of said first branches and a third of said plurality of branches to energize both windings of a predetermined type magnet to control said type shaft stopping means; means controlled upon the closing of said second branch for starting the rotation of said shaft; and a clearing-out relay operated after the printing operation to restore the selecting circuit to normal.

4. In a printing telegraph system, the combination of a plurality of branch circuits; a plurality of type magnets therein, each having two windings, the two windings of each of said magnets in different branches; a rotatable type shaft carrying a plurality of characters thereon; means controlled by both of said windings for stopping said shaft to bring any of said characters into printing position; selective means actuated by two consecutive impulses for closing one of said plurality of branches on the first impulse to energize one winding of a predetermined type magnet; a relay in said branch for closing a second of said branches; a third branch closed by the second impulse to energize the second winding of a predetermined type magnet; and a relay controlled by said selective means for delaying the printing until after the cessation of the second impulse.

5. In a printing telegraph system, a plurality of branch circuits; a plurality of relays therein, each having two windings, the two windings of each relay in different branches; a rotatable type shaft carrying a plurality of characters thereon; means in a plurality of said branches for closing a second of said plurality of branches to energize one winding of a predetermined relay; a starting relay in said second branch; means controlled thereby for starting the rotation of said type shaft; and means in another of said plurality of branches for closing an additional branch to energize the second winding of a predetermined relay for preventing the actuation of said starting relay.

6. In a printing telegraph system, a plurality of branch circuits; a plurality of relays therein, each having two windings, the two windings of each relay in different branches; a rotatable type shaft carrying a plurality of characters thereon; a starting magnet; means controlled thereby for starting the rotation of said type shaft; means for closing one of said plurality of branches; means therein for closing a second of said plurality of branches to energize one winding of a predetermined relay and control the energization of said starting magnet; means for closing a third of said plurality of branches to energize the second winding of a predetermined relay; and an armature

controlled by said predetermined relay for stopping said type shaft in position to print a predetermined character.

7. In a printing telegraph system, the combination of a selecting circuit comprising a plurality of branches; a plurality of type magnets therein; each having two windings, the two windings for each of said magnets in different branches; a rotatable type shaft 10 carrying a plurality of characters thereon; means controlled by both said windings for stopping said shaft to bring any of said characters into printing position; means in one of said plurality of branches for closing 15 a second of said plurality of branches; selecting means controlled by two consecutive impulses for consecutively closing one of said first branches and a third of said plurality of branches to energize both windings of a predetermined type magnet to control 20 said type shaft stopping means; a relay in said secondly closed branch; means con-

trolled thereby for starting the rotation of said shaft; a clearing-out relay operating after the printing operation to restore the 25 selecting circuit to normal; and a guard relay controlled by said selecting means for delaying the operation of said clearing-out relay until after the cessation of the second impulse actuating the selecting means. 30

In witness whereof, I hereunto subscribe my name, this 6th day of December A. D. 1912.

ARTHUR H. ADAMS.

Witnesses:

FRANK TOOHEY,
G. DE HERSY.

In witness whereof, I hereunto subscribe my name this 17th day of December A. D. 1912.

AMOS F. DIXON.
